N. STRAMAGLIA

WINDOW SCAFFOLD

Filed Sept. 25, 1926

Patented Apr. 10, 1928.

1,665,991

UNITED STATES PATENT OFFICE.

NICOLA STRAMAGLIA, OF CHICAGO, ILLINOIS.

WINDOW SCAFFOLD.

Application filed September 25, 1926. Serial No. 137,737.

This invention relates to certain novel improvements in window scaffolds and has for its principal object the provision of an improved construction of this character which will be highly efficient in use and economical in manufacture.

Among the several objects of the invention is the provision of a device of this character which may be expeditiously operatively associated with a window structure to provide a scaffold platform support and one which will assure safety.

Other objects will appear hereinafter.

The invention consists in the novel combination and arrangement of parts to be hereinafter described and claimed.

The invention will be best understood by reference to the accompanying drawing showing the preferred form of construction and in which:

Fig. 1 is a vertical sectional detail view of a window construction illustrating the invention in applied position and showing certain parts of the invention in section.

Fig. 2 is a fragmentary sectional detail view taken substantially on line 2-2 of Fig. 1, and

Fig. 3 is a sectional detail view taken substantially on line 3-3 of Fig. 1.

In the drawing 10 indicates a window construction, 11 the head of the window construction, 12 and 13 the side jambs and sill of the window construction, respectively.

With this construction I associate my improved window scaffold which includes a supporting bar 14 functioning to support the scaffold plank 15. The inner end portion 16 of the supporting bar extends substantially at right angles with respect to

the major portion of the supporting bar and is provided with a tapped hole 17 to receive the adjusting screw 18 including a plate 18' to which the screw 18 is connected by a ball and socket connection 19' and is pro-

vided with a handle 19. The outer end 14' of the bar 14 is bent substantially rectangular to provide a seat 23 for the scaffold plank 15. The portion 21' of this end portion is adapted to be drawn in clamping re-

lation with the face 20 of the head 11. Secured as at 21 to the bar 14 is an end portion 22 of the brace 32. This end portion 22 has an angled end portion 24 which functions to prevent sidewise displacement of the scaffold plank when disposed upon the seat.

Secured to the under side of the bar 14

is an annular flange 26 of a sleeve 27 threaded interiorly as at 28. The flange 26 is secured to the bar through the medium of bolts 29. The sleeve 27 has connected to its lower end portion as at 30 a collar 31 which is formed as an integral part of the brace 32.

The sleeve 27 slidably receives a collar 35 having formed on opposite sides thereof bifurcated ears 36 to which end portions 37 of elements 38 of a turnbuckle structure 39 are connected. The elements 40 of the buckle structures 39 define forks 41 which are adapted to have clamping relation with the side jambs 12 and these forks carry clamping elements 40' including screws 41' having connection with plates 42' by ball and socket connections 43'. The collar 35 may be adjusted in desired position longitudinally with respect to the sleeve 27 and fixed in such adjusted position through the medium of a set screw 42.

When the forks 41 are forced into clamping relation with respect to the side jambs 12 it will be manifest that these forks together with the cooperation of the turnbuckle structure 39, clamping elements 40', and collar 35 function to brace the supporting sleeve against lateral movement and cooperate with the supporting bar to provide a secure scaffold plank support.

The sleeve 27 is adapted to receive a screw shaft 43 and this screw shaft 43 defines at its lower end portion an inverted frusto conically shaped end portion 44 carrying a handle bar 45.

To complete the invention I provide a bearing structure for the screw shaft 43 whereby the screw shaft may be expeditiously rotated for threaded engagement within the sleeve 27. This structure includes a clamp 46 which is clamped to the sill 13 through the medium of adjusting screws 47, one engaging on top of the sill and the other engaging at the side of the sill and both including plates 47' having end portions working in slots 48'. Secured to this clamp 46 is a bearing structure 48 which includes a base 49 providing a recess 50 within which the bearing rings and ball bearings 51 are confined when the extreme end portion of the conically shaped end 44 is projected into the bearing structure. These bearing rings 51 are held against displacement through the medium of a cap 52 which is secured to the base 49 as at 53. By rotating the screw

2
shaft 43 the sleeve 27 will be adjusted longitudinally relative to the screw shaft and thus force the supporting bar and the clamp 46 into clamping engagement with respect to a the head and sill 11 and 13, respectively.

From the above description it will be manifest that I provide a device which can be expeditiously mounted in place and when mounted will assure safety to permit one to step upon the scaffold plank.

While I have illustrated and described the preferred form of construction for carrying my invention into effect, this is capable of variation and modification without departing from the spirit of the invention. I therefore, do not wish to be limited to the precise details of construction set forth, but desire to avail myself of such variations and modifications as come within the scope of the appended claims.

The invention having been set forth, what I claim as new and desire to secure by Letters Patent is:

1. A scaffold structure of the class described including a supporting member adapted to support a scaffold plank, means for clamping the supporting member to the head of a window construction, means for forcing the supporting member against the bottom of the head, and means for clamping one end portion of said last mentioned means to the sill of the window construction, said clamping means embodying portions extending parallel to said head adapted to prevent lateral movement of said structure.

2. A scaffold structure including a supporting bar having one end portion extending in angular direction with respect to the major portion of the supporting bar and

40 having an opposite end portion bent to provide a seat, means carried by said angled end portion for drawing said opposite end portion in bearing engagement with the head of a window construction, and means for forcing said supporting bar into engagement 45 with the head of said window construction.

3. A scaffold structure including a supporting bar having one end portion extending in angular direction with respect to the major portion of the supporting bar and 50 having different opposite end portions bent substantially rectangularly to provide a seat for the accommodation of a plank, an adjustable member carried by the angled end portion and operative on the face of the head of a window construction for clamping the head between a portion of the seat and said adjustable member, a clamping structure adapted to have clamping engagement 55 with the sill of said window construction, means having operative connection with the supporting bar and the clamping structure, said means including two movable members 60 operative for forcing the supporting bar and clamping structure into bearing relation with the head and sill respectively, a brace member having one end portion connected to one of said members and having an opposite end portion connected to the seat with a portion of said opposite end portion projecting 65 above said seat and functioning to prevent sidewise displacement of said scaffold plank, and means for detachably clamping said 70 forcing means to the jambs of said window construction.

75 In testimony whereof I affix my signature.

NICOLA STRAMAGLIA.
